UNITED STATES PATENT OFFICE.

PETER C. FRITZ AND HARRY C. CRAWFORD, OF GERMANTOWN, PENNSYLVANIA.

AUTOMATIC LUBRICATOR FOR DIE-STOCKS.

1,231,591.

Specification of Letters Patent.

Patented July 3, 1917.

Application filed January 3, 1916. Serial No. 69,767.

To all whom it may concern:

Be it known that we, PETER C. FRITZ and HARRY C. CRAWFORD, citizens of the United States, residing at Germantown, in the 5 county of Philadelphia and State of Pennsylvania, have invented new and useful Improvements in Automatic Lubricators for Die-Stocks, of which the following is a specification.

Our invention relates to new and useful 10 improvements in automatic lubricators for die stocks, and has for its object to provide an exceedingly simple and effective device of this character whereby the dies carried by 15 the die stock may be adequately, thoroughly, readily and easily lubricated while in use.

A further object of the invention is to provide a lubricator for die stocks employing the handle of the die stock as the casing of 20 the lubricator, said handle being closed at both ends and having a duct leading therefrom to a point adjacent the dies whereby the lubricant will be conveyed direct to the place of use.

25 A still further object of the invention is to divide the chamber within the handle into two compartments by a sliding valve, one of said compartments having an outlet duct leading therefrom, said compartments being in communication when the valve is positioned to close the outlet duct, but having said communication interrupted when the outlet duct is open, said valve when actuated serving as a piston to vary the size of 30 the compartments and positively force the lubricant through the outlet duct.

Another object of the invention is to provide a lubricator for die stocks having a 35 sliding valve so constructed as to divide the interior of the handle into two compartments and to further sub-divide one of said compartments to produce a spring chamber in which is situated a spring for normally 40 forcing the valve in that direction which will close the outlet duct.

Still another object of the invention is to provide a closure for the outer end of the handle having a stuffing box through which passes the valve stem, the latter carrying a 45 collar for further sealing the opening through the closure and acting as a stop to limit the closing movement of the valve.

Another object of the invention is to provide said closure with a button chamber for 50 housing the end of the valve stem and the

button carried thereby to prevent an object coming in contact with the button or stem which might injure or break the valve stem or button.

With these ends in view, our invention 60 consists in the details of construction and combination of elements hereinafter set forth and then specifically designated by the claims.

In order that those skilled in the art to 65 which this invention appertains, may understand how to make and use the same, we will describe its construction in detail, referring by numerals to the accompanying drawing forming a part of this application in 70 which—

Figure 1, is a plan view of a die stock showing our invention applied thereto, a portion of one of the handles being broken away.

Fig. 2 is a side elevation thereof, partly 75 in section to clearly illustrate the construction; and

Fig. 3, is a section at the line 3—3 of Fig. 2.

In carrying out our invention as here embodied 2 represents a die stock constructed to receive the cutting dies 3 and having a work opening 4 across which project the dies 3. The die stock is further provided with 80 handle sockets 5 in which are mounted the handles 6 in any well known and approved manner here shown as threaded therein.

In the inner end of one of the handles 6 or the end which engages the socket 5 is 85 mounted a bushing 7 of some suitable metal such as brass and one end of said bushing is beveled as at 8. This bushing is provided with a small outlet opening 9 registering with an opening 10 in the handle and in 90 the latter is set one end of the outlet duct 11 comprising a piped elbow 12 and a tube 13 connected to the elbow 12 by a suitable union, said tube leading to or projecting into the work opening 4 of the die stock, so 95 as to convey the lubricant from the interior of the handle 6 to the work and cutting dies.

The inner end of the handle 6 is threaded 100 interiorly as at 14 in which is threaded a closure bushing 15 having a central opening 16 normally closed by a plug 17 threaded therein. The outer end of the handle 6 is also threaded interiorly as at 18 to receive 105 the exteriorly threaded closure 19, said closure having a flange 20 milled around its 110

outer circumference adapted to cover the outer end of the handle as plainly shown in Fig. 2.

From the inner end of this closure 19 projects a stuffing box 21 having an opening 22 therein communicating with the interior of the handle and with the packing chamber 23 in which is arranged the packing 24 for the valve stem 25, said packing being held in place by the gland 26 threaded into the packing chamber. The closure 19 is also provided with a button chamber 27 open at its outer end, and into which projects the outer end of the valve stem 25, said outer end of the valve stem carrying an operating button 28 mounted thereon in any suitable manner and adapted to operate within the button chamber 27, so that said button will be housed at all times to prevent it being injured or broken when coming in contact with an object should the die stock fall or hit an object while in use. The valve stem 25 passes through the closure 19 into the lubricant chamber formed by the bore 25 of the hollow handle 6, and the inner end of said valve stem is attached to the valve 30. The valve 30 is arranged to slide in the bushing 7 and consists of a head 31 having passageways 32 preferably in the form of notches produced in the inner edge thereof, a base 33 having passageways 34 entirely therethrough, said base and head being connected by a neck 35 of less diameter than said base or head, thereby producing a feeding chamber 36 entirely around said neck and between it, the bushing, the head and base. The head 31 of the base divides the oil chamber 29 into two compartments, one being the feeding chamber 36 and the other the main chamber or reservoir 37, while the base of said valve sub-divides the innermost compartment into said feeding chamber 36 and a spring chamber 38.

In the spring chamber 38 is situated the helical spring 39, one end thereof resting against the closure bushing 15 as the immovable object, and the other end resting against the base of the valve as the movable object for normally forcing said valve outward or in that direction which will dispose the base of the valve across the opening leading to the outlet duct, so that said outlet duct is normally closed to the lubricant and when said outlet duct is closed, the passageways or notches 32 place the chamber 37 on one side of the valve head in communication with the chamber on the other side thereof, thus permitting the lubricant to freely flow into the feeding chamber 36 and the spring chamber 38.

As will be noticed in Fig. 2, the base 33 and the head 31 each snugly fit within the bushing 7, so that the latter is of less diameter than the interior diameter of the handle, and when said head partially projects from

the bushing there is a space between said head and the walls of the handle to permit the lubricant to flow into the passageways 32.

In order to regulate the outward or closing movement of the valve a collar 40 is mounted on the valve stem 25 adjacent its outer end which is adapted to engage the inner end of the closure 19 or its stuffing box 21 when the valve is in the position shown in Fig. 2, and said collar also acts as a seal so that when the valve is closed, the lubricant will be prevented from reaching the opening 22 and the packing in the stuffing box, thus assisting in the prevention of leakage.

In practice at any time while the die stock is in use and a lubricant is contained within the handle between the two closures, the operating button 28 may be pressured or forced inward to actuate the valve against the action of the spring 39. As the valve is actuated the passageways 32 in the head 31 of the valve will be closed by the bushing 7 thus separating the lubricant in the inner end of the handle from the lubricant contained in the outer end thereof. At about the same time the base 33 of the valve will be moved beyond the outlet opening leading to the outlet duct, and the continued movement of the valve will shorten the length of the chamber at the inner end of the handle, thereby forcing the lubricant from the spring chamber through the passageways 34 into the feeding chamber 36 and from the feeding chamber into the outlet duct and forced through said outlet duct on to the work and cutting dies, thus positively lubricating said dies.

As soon as the pressure is relieved from the operating button 28 the spring 39 will force the valve to its normal position as shown in Fig. 2, so that the base 33 of said valve will close the outlet opening to the outlet duct and will move the outer ends of the passageways 32 beyond the bushing 7 or into communication with the beveled edge thereof, so as to establish the communication between the chambers on each side of the valve head 31. The valve will be forced outward until the collar 40 contacts with the collar 19, thus stopping the valve and limiting its further outward movement.

In order to take the lubricator apart or to refill the same with lubricant, the tube 13 is disconnected from the elbow 12 by means of the union and the handle then removed from its socket. After the handle is removed, the plug 17 may be withdrawn and the lubricant placed in the handle through the opening 16, after which the parts are replaced and the device is again ready for use.

Of course we do not wish to be limited to the exact details of construction as herein shown, as these may be varied within the

limits of the appended claims without departing from the spirit of our invention.

Having thus fully described our invention, what we claim as new and useful, is—

- 5 1. In a device of the character stated, a die stock, a combined handle and lubricant reservoir supported thereby, an outlet duct leading therefrom, a closure bushing having an opening therethrough mounted in the inner end of the handle, a plug for closing said opening, a closure for the outer end of the handle, a valve dividing the reservoir into a number of compartments, said valve also controlling the outlet duct and the communication between certain of said compartments and means for actuating said valve.
- 10 2. In a device of the character stated a die stock, a combined handle and lubricant reservoir supported thereby, an outlet duct leading therefrom, a closure bushing having an opening therethrough, mounted in the inner end of the handle, a plug for closing said opening, a closure for the outer end of the handle, a valve dividing the reservoir into a number of compartments, said valve also controlling the outlet duct and the communication between certain of said compartments, means for forcing said valve in one direction to normally close the outlet duct and means attached to said valve and passing through the outer closure for actuating the valve against the action of the spring to open the outlet opening.
- 15 3. In a device of the character stated a die stock, a combined handle and lubricant reservoir supported thereby, an outlet duct leading therefrom, a closure bushing having an opening therethrough mounted in the inner end of the handle, a plug for closing said opening, a closure for the outer end of the handle having a button chamber, a stuffing box formed therewith, a flange exteriorly milled formed with said outer closure, a valve dividing the reservoir into a number of compartments, said valve also controlling the outlet duct and the communication between certain of said compartments, a valve stem attached to the valve passing through the stuffing box of the outer closure and projecting into the button chamber, and a button mounted on the outer end of said valve stem.
- 20 4. A device of the character stated com-

prising in combination, a die stock, a combined handle and reservoir supported thereby, an outlet duct leading therefrom, closures for the ends of said handle and a sliding valve within the handle comprising a head having passageways, a base having 60 passageways therethrough and a neck of less diameter than the head and base connecting them together.

5. A device of the character stated comprising in combination a die stock, a combined handle and reservoir supported thereby, an outlet duct leading therefrom, closures for the ends of said handle, a sliding valve within the handle comprising a head having passageways, a base having 65 passageways therethrough and a neck of less diameter than the head and base connecting them together, said valve dividing the reservoir into a number of compartments and arranged to control the passageways between certain of said compartments and the outlet duct, and means for actuating said valve.

6. A device of the character stated comprising in combination a die stock, a combined handle and reservoir supported thereby, an outlet duct leading therefrom, closures for the ends of said handle, a sliding valve within the handle comprising a head having passageways, a base having 80 passageways therethrough and a neck of less diameter than the head and base connecting them together, said valve dividing the reservoir into a number of compartments and arranged to control the passageways between certain of said compartments and the outlet duct, a spring for normally forcing the valve in that direction to close the outlet duct and open the passageways between certain compartments and a valve 85 stem having a button on its outer end for actuating said valve in the opposite direction to open the outlet duct and close the passageways between said certain compartments.

In testimony whereof, we have hereunto affixed our signatures in the presence of two subscribing witnesses.
